T.H. Barlow,

Making Cut Nails.

N° 11,114,

Patented June 20, 1854.

Fig. 2.

UNITED STATES PATENT OFFICE.

THOMAS H. BARLOW, OF LEXINGTON, KENTUCKY.

CUT-NAIL MACHINE.

Specification of Letters Patent No. 11,114, dated June 20, 1854.

To all whom it may concern:

Be it known that I, THOMAS H. BARLOW, of Lexington, in the county of Fayette and State of Kentucky, have invented certain new and useful Improvements in Nail-Machines; and I do hereby declare the following to be a full, clear, and exact description of the same, reference being had to the accompanying drawings, which represents a perspective view of the entire machine in Figure 1 and a plan of the shears and parts of the stocks and shaft in Fig. 2.

Similar letters in both the figures denote like parts.

The nature of my invention relates to the peculiar method of shearing the blank from the nail plate; to the so arranging of the pairs or sets of shears and grippers, as that they shall be operated by one rock shaft; and to the method of feeding up the nail plate to the pairs or sets of shears and grippers.

To enable others skilled in the art to make and use my invention, I will proceed to describe the same with reference to the drawings.

A bed plate A, of any suitable construction is made, upon which the pillar blocks B, B, are arranged for forming a bearing for the cam shaft C, which may be rotated from any first mover. On or near the center of the cam shaft C, is placed a cam D, which operates in the yoke E, of a lever F, which lever is connected to the rock shaft G, and by means of said cam shaft, cam, yoke and lever, motion is communicated to said rock shaft.

The vibrating stocks H, H, each of which carries its respective cutter or shear I, I, are connected permanently with the rock shaft G—one on each side of said shaft, so that they move alternately toward and from their respective stationary cutters or shears J, J, which are arranged on the permanent or immovable stocks K, K. The faces of the stationary stocks K, K, on which the cutters J, J, are placed, stand at an angle of about forty-five degrees with the nail plate L, while the faces of the stocks H, H, are almost at right angles to the nail plate. The edges of the cutters J, J, are so beveled off on their undersides as that the top surfaces of the cutters I, I, will move in contact therewith, and thus the blank is cut off from the plate, the shear of cut being from both sides, and the shape of the cut

is square with the sides of the nail plate. The pairs or sets of cutters I J—I J, should be so inclined in their beds in the stocks as to cut the blanks from the plate alternately “head and point,” as it is termed, to keep the end of the nail plate as nearly square or uniform as possible. The stocks K, K, should be susceptible of adjustment, by set screws or otherwise, so as to be adjusted to their fellows on the rock shaft—and the cutters or shear blades I, J, may also be made adjustable in their beds by set screws or otherwise. After the stocks K, K, are adjusted they are then immovable—their mates or fellows H, H, oscillating to and from them by the motion of the rock shaft to which they are attached. That portion of the stocks immediately underneath the cutters, form the gripping jaws, which seize the blank the moment it is cut from the nail plate and hold it firmly until the headers (to be hereafter described) come up and form the head, when the jaws are opened by the receding of the movable stock, and the nail drops out finished.

On the shaft C, are arranged two cams L, L, for operating the heading levers M, M—there being one header for each of the pairs of sets of cutters or shears. These heading levers oscillate on their journals (one of which is the block N, and the other at O) at proper intervals so as to head the blank the moment it is caught by the gripping jaws.

The method of feeding up the nail plate is as follows, viz: Two upright supporting pieces P, P, are arranged on the bed plate or table, immediately over the cutters, the tops of which are united by a cross piece Q. The nail plate holder R, passes through a slot or mortise in the cross piece Q, and extends down and through a sliding bar S, which is pushed to and fro, by means of the arms T, T, arranged, one on each of the heading levers M, M. In this nail plate holder or the shank or handle thereof is placed a series of pins or teeth 1, 2, 3, &c., which should extend from the top to the bottom of said nail plate holder (although represented but in a portion thereof)—which teeth catch into and are released by a sliding escapement U, so as to let down said holder the distance between the pins or teeth, at every back and forward motion of the escapement—or in other words one half the distance by the forward, and the

other half of the distance by the backward movement of said escapement. The escapement may be constructed and operated in a variety of ways—the one here represented is however quite simple, and consists of two parallel plates, just the distance apart that it is required to drop the nail plate at each operation of the cutters. The teeth are caught first upon the upper plate, which slides out from under them when they drop on the second or under one, and so on. The escapement should be made to turn on its pivoted point so that it may be readily removed for raising up the nail plate holder, or when furnishing it with a new plate and may be slid back against a guide *a* and held by a button *b*, when in place.

V, is a vibrating lever hinged at *c*—its lower end being connected to the sliding bar *S*, at *d*, and its upper end to the escapement *U*, at *e*. As the bar *S* is thrown to one side and then to the other, by the arms *T*, it vibrates the nail plate holder, and the nail plate in it, first bringing it over one set or pair of cutters, and then over the other set or pair, alternately, but in all cases so that the thick part of the blank cut from the plate, or that part on which the head is to be formed, shall be on the outer sides of said pairs or sets of cutters; and at the precise instant that the nail plate is over either of the cutters the escapement allows it to drop the proper distance to constitute the necessary feed. The nail plate holder standing perpendicularly, or nearly so over the cutters, it falls by its own gravity the moment it is released by the escapement, and thus the escapement becomes the means of feeding up, and gaging the feed, of the nail plate. The escapement as before mentioned may be made and applied, to the feeding up, and gaging of the feed, of nail plates in various ways and I do not intend to confine myself to the use of the one specially described herein, as others are equally capable of performing the same function, and I intend to so apply them if found essential to my invention.

There is a very great mechanical certainty of the nail plate being in the proper posi-

tion for being fed up to the cutters, because as the header comes up to head the blank just cut off, its arm *T*, pushes over the slide *S*:—now the slide in moving in one direction, operates the escapement in a contrary direction through the centrally pivoted lever *V*, and the sliding of the escapement lets down the nail plate to the cutters at the exact time; and I thus by a simple contrivance, and by the very parts with which they must work in perfect harmony, accomplish the feeding up of the nail plate. 55

It is obvious that this machine may be adapted to the making of nails of all sizes, down to the smallest tacks, as from its simple combination of parts for rapid work, and its perfect and certain automatic feed it is peculiarly applicable to the purposes designed. 65

Having thus fully described the nature 70 of my invention what I claim therein as new and desire to secure by Letters Patent is,

1. In combination with the pairs of fixed stocks and cutters *K, J*, the vibrating stocks 75 and cutters *H, I*, when said vibrating stocks and cutters are so arranged as to be capable of being operated from one rock shaft, by one cam and lever, and the pairs or sets of stocks constitute the gripping jaws for 80 holding the blank while it is being headed, and thus dispensing with the usual mode of gripping, substantially as described.

2. I also claim in combination with the vertical oscillating nail plate holder the escapement *U*, or its equivalent for the purpose of gaging, and feeding up the nail plate to the cutters and grippers, substantially as described. 85

3. I also claim the operating of the nail 90 plate holder from the heading levers, through the medium of the arms *T*, sliding bar *S*, lever *V*, and escapement *U*, or their mechanical equivalents, substantially as described.

THOS. H. BARLOW.
